UNITED STATES PATENT OFFICE.

GUS J. KOWALSKI, OF DETROIT, MICHIGAN.

PROJECTILE.

1,274,281.

Specification of Letters Patent Patented July 30, 1918.

Application filed February 16, 1918. Serial No. 217,582.

To all whom it may concern:

Be it known that I, GUS J. KOWALSKI, a citizen of the United States, and a resident of Detroit, in the county of Wayne and State 5 of Michigan, have made certain new and useful Improvements in Projectiles, of which the following is a specification.

My present invention relates generally to projectiles, and more particularly to certain 10 improvements therein calculated to assist the aerial flight thereof, my object being the provision of simple, inexpensive and effective means whereby to avoid the usual retarding vacuum at the rear square end of a 15 projectile, and to do this by certain means permitting the ordinary action of the propelling charge within the gun with maximum effect.

In carrying out my invention I provide a 20 collapsible cone for the rear end of the shell, the collapsible sections of which are normally held against the rear square end of base of the shell in such manner as to permit of the usual effect of the propelling 25 charge within a gun upon the shell base, together with means which are normally held in retracted position for moving the several 30 sections of the cone into active relation to one another, the said means being automatically 35 acted upon during discharging movement of the projectile from the gun so that upon its discharge the rear cone will be completely formed in order to obviate the formation 40 of a vacuum at the base of the shell during flight.

With the above in mind, my invention may be thoroughly understood in its several 45 aspects from the accompanying drawings forming a part of this specification, and wherein:

Figure 1 is a central longitudinal section through a projectile provided with my improvements.

Fig. 2 is a side elevation thereof.

Fig. 3 is an enlarged central section through the rear end of the projectile with my improvements in collapsed or retracted position.

Fig. 4 is an elevation of the rear end of the shell with my improvements in active position, and

Fig. 5 is a detail section through a portion of the shell illustrating a slightly modified form.

Referring now to these figures, I have shown a projectile generally indicated at 10

in Fig. 1 in particular, which may be of any suitable construction except in so far as the application of my invention to the rear square end or base thereof, it being essential that this shell shall have an axial bore 11 projecting inwardly from its said rear square end or base with a radial opening 12 parallel to its rear square face 13, and communicating at the inner end thereof by means of a reduced opening with the axial bore 11 adjacent the rear end of the latter, radial bore 12 having an enlarged counter-bore 14 at its outer end opening through the surface of the shell. In the axial bore 11 is a plunger 15, against the forward inner end of which a spring 16 bears, said spring being compressed within the inner portion of the bore 11 to normally thrust the plunger 15 rearwardly to the position shown in Fig. 75 1. This plunger 15 has an annular groove 17 adjacent its rear end which, in the inner forward and retracted position, receives the inner end of a lock pin 18 mounted in the radial bore 12, and having an outer rigid 80 head 19 slidable in the counter-bore 14. This lock pin 18 is controlled by a spring 20 which bears against its head 19 to normally thrust the pin outwardly to released position shown in Fig. 1, and out of engagement with the plunger 15, permitting the spring 16 of the latter to act upon and thrust the plunger rearwardly.

At its rear extremity the plunger 15 has a rigid conical head 21, which in the forward retracted position of the plunger abuts the base surface 13 of the projectile 10, as seen in Fig. 3, this head 21 forming the apex of a hollow rear cone for the projectile 10 consisting in addition to the head 21, of a series of frusto conical rings 22 freely movable with respect to one another, and a forward outer ring 23, which latter is either secured to the base of the projectile or formed as an integral part thereof, as seen in Figs. 1 and 3.

The base surface 13 of the projectile has a series of clips 24 in which the forward edges of the several rings 22 are engaged in the collapsed or retracted position, as seen in Fig. 3 before and at the time the projectile is fired, so as to thus permit of the usual maximum effect of the propelling charge against the projectile base. At this time, the time the shell is fired, the plunger 15 is held in retracted position by the lock pin 18, the latter being thrust inwardly and

held in innermost position against the tension of its spring 20 by a bell crank lever 25 fulcrumed within the counter-bore 14, one arm of this lever acting against the pin 5 head 19 and the other arm being engaged by a latch piece 26. This latch piece 26 is slideable within a groove or kerf 27 of the projectile adjacent its base 13, and in a direction at an angle to the longitudinal axis of 10 the projectile corresponding to the rifling of a gun bore, so that when the projectile is introduced within the gun bore and fired, the latch piece 26 will be moved by frictional engagement with the base of the rifle grooves 15 and shifted free of the lever 25 so as to permit of outward movement of the latter into the rifle groove, such movement being insufficient, however, to permit of full release of the lock pin 18 from the plunger 15. 20 Thus the projectile passes from the bore of the gun from which it is fired with the parts still in the retracted position, but instantly upon its final discharge from the mouth of the gun, lever 25 moves to the 25 fully released position shown in Fig. 1, permitting spring 20 to thrust lock pin 18 outwardly for its full movement, and its release from the plunger 15. The latter instantly moves rearwardly under tension of 30 spring 16 to the operative position shown in Fig. 1, forcing the head 21 rearwardly and thrusting the frusto-conical rings 22 rearwardly therewith to form with the ring 23 the full cone as seen in Fig. 2, whose purpose is to prevent the formation of a vacuum at the rear end or base of the projectile during its flight. In this way retardation of the projectile is avoided, its true line of flight better preserved and its rotary movements upon its longitudinal axis better preserved. 35

By reference again to Fig. 1, it will be noted that the inner surfaces of the cone forming rings 22 and 23 have inner guide 40 pieces 28 located at spaced points there-around, with which the inner or forward edges of the rings 22 and the head 21 cooperate to guide these rings, and this head into the active position shown in Fig. 1, and 45 obviate danger of canting of the rings 22 or their improper seating in connection with one another in the active cone forming position. 50

As seen in Fig. 5 I may employ a link 29 connecting the head 19 of the lock pin 18, with the respective arm of the bell crank lever 25, this change as well as other changes in the details hereinbefore described being well within the invention and to be 55 understood as a part thereof.

I claim:—

1. An aerial projectile having a squared rear end or base and provided with means 60 normally collapsed adjacent to said base for forming a cone shaped extension covering

the base, and a normally inactive member for guiding said sections into extended operative position.

2. An aerial projectile having a cone shaped rear extension consisting of telescoping sections and automatically releasable means for normally retaining the said sections in inactive position at the adjacent end of the projectile. 70

3. An aerial projectile having an axial bore extending therein from its rear end, a plunger movable in the bore, a spring engaging the inner ends of the plunger to normally force the latter rearwardly, a radially extending locking pin normally engaging the plunger to hold the latter in inner retracted position, a shiftable latch member normally holding the lock pin in engaged position, a conical head carried by the outer rear end of the plunger, a series of frusto conical rings of varying diameters telescoped within one another at the base of the projectile and including an outer ring secured to the projectile, and an inner ring engageable by the said conical head 80 of the plunger for the purpose described. 85

4. An aerial projectile having an axial bore extending therein from its rear end, a plunger movable in the bore, a spring engaging the inner ends of the plunger to normally force the latter rearwardly, a radially extending lock pin normally engaging the plunger to hold the latter in inner retracted position, a shiftable latch member normally holding the lock pin in engaged position, a conical head carried by the outer rear end of the plunger, a series of frusto conical rings at the base of the projectile of varying diameters and including an outer ring rigid with the base of the projectile, the other rings being in telescoping relation to one another and the said rigid ring and including an inner ring engageable by the said conical head, and means located upon the base of the projectile for normally supporting said movable rings thereon in detachable relation. 100 105

5. A projectile having a sectional cone shaped extension at the rear end thereof, the sections of which are engageable and disengageable by movement in a direction parallel to the longitudinal axis of the projectile, means for normally supporting the said sections in detached relation at the rear end of the projectile, and means releasable when the projectile is propelled from a gun for shifting the said sections into active relation forming the cone. 110 115

6. A projectile provided with a collapsible cone shaped extension at its rear end, and automatically releasable means for normally maintaining the cone in the collapsed position. 120 125

7. A projectile provided with a collapsible cone shaped projection at its rear end 130

normally held in collapsed position, means for extending the same to active position, and latch controlled means engaging said first named means to normally hold the same 5 inactive including a latch member automatically shiftable to released position in the bore of a gun.

8. A projectile having an extensible and

collapsible cone shaped extension at its rear end normally held in collapsed position, 10 and automatically controlled means for guiding the same to active position when the projectile is discharged from the gun, said means being normally locked within the rear portion of the projectile.

GUS J. KOWALSKI.
